REMOVAL OF WASTE RAYON FROM
BOBBINS

Moulton L. Hudson, Enka, N. C., assignor to
American Enka Corporation, Enka, N. C., a cor-
poration of Delaware

Application May 22, 1941, Serial No. 394,731

10 Claims. (Cl. 28—19)

This invention relates to apparatus employed in the textile industry for stripping residual strand material from bobbins and the like. More particularly the invention concerns an apparatus for stripping residual or waste yarn from bobbins wherein the yarn body is severed to facilitate its removal.

While this invention is of wide applicability in connection with the removal of yarn from holders of all types, it is of particular utility in connection with the removal of waste yarn from the perforate tubular bobbins employed in the manufacture of rayon. In the manufacture of rayon the yarn withdrawn from a coagulating bath is collected upon a foraminated cylindrical spinning spool or bobbin. The wound package is then subjected upon the spool to various after-treating operations such as washing, desulfurizing, bleaching and drying. The yarn shrinks upon drying and the inner layers adjacent the hard surface of the bobbin are prevented from contracting properly, so that the physical properties of these inner layers vary widely from those of the outer layers, which shrink more normally. Therefore, upon rewinding and twisting the yarn on a twisting machine, the compact layers adjacent the bobbin are allowed to remain thereon and are treated as waste. This waste yarn must be removed before the bobbin can again be placed in production. A similar situation arises when, in order to meet the requirements of the fabric manufacturing trades, the twisted yarn is unwound from the twisting bobbin and reeled into skeins or the like. The yarn nearest the twisting bobbin does not receive the same degree of twist as the upper layers and these inner layers are, therefore, left upon the bobbin for later removal.

The problem of finding a rapid and economical method of removing this residual or waste yarn from bobbins has occupied the rayon industry for many years. One method now in common use involves the employment of a knife or similar instrument manually wielded by a skilled operator, whereby the yarn body, which has been previously moistened to decrease its resistance, is severed to facilitate its removal from its supporting bobbin. This method is relatively satisfactory, but is slow and hence expensive from the point of view of labor cost. Further, the danger of injury to the surface of the bobbin by the edge of the knife is considerable and excessive bobbin replacement has been necessary.

In order to save time and labor and to increase the efficiency of the stripping operation, machines have been proposed whereby the bobbin

can be mechanically or otherwise relieved of the waste yarn thereon. In view of the danger of using a knife, the object of these machines has been generally to remove the waste yarn by means not involving a cutting operation. One suggested method involved feeding waste-bearing bobbins to a machine, directing a current of air against the bobbin to loosen the yarn and rotating the bobbin in a direction counter to the direction in which yarn was wound, and then drawing off the waste yarn. This method has proved slow and cumbersome and therefore unsatisfactory. It has also been proposed to remove the waste by scraping; that is, by pushing the yarn body from one end of the bobbin to the other. With tightly packed bobbins, such as are produced in the rayon industry, this is impractical, and the danger of scoring the surface of the bobbin is not diminished.

It is generally conceded that the stripping of bobbins is accomplished most rapidly, efficiently and therefore economically if the yarn body can be severed by a hard cutting instrument. The yarn then falls away from the bobbin or is easily removed by hand. Due, however, to the danger of damaging the bobbin, the textile industry has avoided the use of hard cutting implements and has sought the solution to this problem in the use of knives or cutting wheels made of paper or soft rubber. These materials, however, while lessening the danger to the bobbin, are unsatisfactory for the reason that more time is required to sever the yarn and frequent replacement of the cutting instrument is necessary.

U. S. Patent No. 1,109,949 discloses the use of a hard knife blade for severing yarn from the type of spools employed in weaving and like machines, wherein the spool is provided with a deep longitudinal groove in which a knife can be inserted. However, this apparatus is useful only with heavy-bodied spools in which a groove can be made without substantially weakening the spool structure. Furthermore, in order for the cutting operation to be performed without damage to the spool, the spool must be positioned with the groove exactly in line with the knife; a slight deviation from this position rendering the device inoperative. Clearly, such a device would be totally impractical if applied to the type of thin-shelled aluminum bobbins employed in the rayon industry, inasmuch as a groove deep and long enough to make the cutting operation practical would impair the rigidity of the bobbin.

The present invention avoids all of the aforementioned difficulties and, in general, has for its

object an apparatus for severing waste yarn from bobbins by means of a hard knife in such a way that the severance is expeditiously effected without injury to the bobbin surface.

According to this invention, waste-filled bobbins are periodically fed to a gripping means, the bobbin momentarily immobilized, for the automatic severance of the yarn therefrom during the gripping period, the bobbin discharged with the severed yarn clinging thereto, and the waste removed by spraying liquid from above upon the kerf in the yarn body made by the cutting blade thereby maintaining the safety advantages of stripping waste yarn by hand, while effecting enormous savings in operating time.

These and other objects and advantages will appear more fully from the following detailed description of a preferred embodiment of this invention when read in conjunction with the accompanying drawings, wherein:

Figure 1 is a view in side elevation of a preferred form of bobbin stripping machine constructed according to this invention;

Figure 2 is a top plan view of the machine, a portion of the conveyor mechanism and the feed chute being eliminated for convenience in illustration;

Figure 3 is a longitudinal sectional view taken along the line 3-3 of Figure 2 and additionally illustrating the bobbin feed chute;

Figure 4 is a transverse sectional view taken along the line 4-4 of Figure 1;

Figure 5 is a transverse sectional view taken along the line 5-5 of Figure 1;

Figure 6 is a plan view of the discharge end of the conveyor mechanism;

Figure 7 is a detailed elevation to an enlarged scale of a cutter member in operative position;

Figure 8 is a perspective view of the cutter member per se;

Figure 9 is a front view of the lower portion of the cutter member; and

Figure 10 is a view of the lower portion of the cutter member from the rear.

In the drawings, the numeral 1 designates generally a frame in which the bobbin stripping mechanism is mounted, and 2 a flat table provided with a cut out portion at 3 for the accommodation of an endless conveyor for feeding waste-filled bobbins to and discharging waste free bobbins from operative relation with the stripper mechanism.

According to the invention, waste-bearing bobbins are periodically fed to an endless conveyor and periodically advanced thereby to a position adjacent the stripper mechanism. Here each bobbin is temporarily immobilized for the severance of the yarn body by the cutting blade of the stripper mechanism; the conveyor is then again actuated to move the bobbin with the severed waste clinging thereto out of operative relation with the stripper and to bring a succeeding bobbin into position. Once the yarn on the bobbin is severed it is carried along by the conveyor and passed below spraying devices which direct a liquid against the upper surface of the bobbin, thus dislodging the yarn therefrom to complete the stripping operation. The waste yarn, as it drops from the bobbin is caught in a basket while the spray liquid is carried off in a trough mounted therebelow. The empty bobbins are discharged from the conveyor and may be picked up by hand or may be allowed to drop from the conveyor into a box or other suitable container. The mechanisms for operat-

ing the conveyor and yarn severing mechanism are controlled from a common drive shaft, and are so coordinated that during the time the bobbin is immobilized for the yarn severing operation the cutting blade twice traverses the length of the bobbin to insure severance of all of the coils of yarn.

Mounted upon table 2 at opposite sides of the cut-out at 3 are brackets 4 and 5 supporting therebetween a guide rod 6, the ends of which are fixed in bosses 7 and 8 at the upper ends of the brackets. The guide rod functions as a guide and support for a reciprocating mechanism bearing the cutting means designed to sever the body of yarn on the bobbin. Projecting upwardly from boss 7 is an extension 9 bifurcated to receive one end of a lifter rod 10 pivotally mounted upon a pin 11 in extension 9, the purpose of said lifter rod being to raise the cutter blade out of contact with the bobbin during the second return stroke of the reciprocating mechanism after the yarn body on the bobbin has been severed. Lifter rod 10 is spaced vertically from and lies in a plane parallel to guide rod 6, its other end extending beyond and resting in a bifurcated extension member 12 projecting upwardly from boss 8 of bracket 5.

A sleeve 13 is mounted upon guide rod 6 for reciprocating engagement therewith and is provided with a crosshead 14 terminating in a boss 15 having a central bore through which is passed a pin or bolt 17. The forked ends of a cutter bar 18 and a connecting rod 19 are pivotally mounted upon bolt 17 and are held in place by means of nut 20 and lock nut 21.

In order to raise the cutter bar 18 on its return stroke after performing a waste-cutting operation a lifting assembly is provided comprising a pair of lifter links 22 and 23, the lower ends of which are loosely bolted to opposite sides of the cutter bar by a bolt 24 and nut 25, the upper ends of the lifter links being connected by a roller 26 adapted to rest upon the top of lifter rod 10. Roller 26 is loosely mounted upon a bolt 27 passing through the lifter links and fastened by nuts 28 and 29. Lifter links 22 and 23 are provided with slots 30 and 31, respectively, for sliding engagement with bolts 32 and 33 inserted in opposite sides of sleeve 13.

At the forward end of cutter bar 18 is a cutter blade 34 comprising a wedge-shaped portion fastened in a V-shaped slot in the end of the cutter bar by means of bolt 35. The cutter has a downwardly extending shank 36 provided with a forward cutting edge 37 and a forwardly and downwardly projecting foot 38. The lower surface of the foot is made arcuate to fit the surface of a bobbin, and the upper surface is beveled to adapt it for insertion under the coils of yarn on the bobbin. During a cutting operation the cutter bar 18 is maintained parallel to guide bar 6 and lifter bar 10 by means of a spring 39 placed between the cutter bar and sleeve 13, and supported by a pin 40 passing through spring holders 41 and 42 and cutter bar 18, and screw-threaded in the latter for easy adjustment of the spring tension. Of course, spring 39 serves resiliently to hold foot 38 against the bobbin being subjected to treatment.

Sleeve 13 is further provided at its forward end with a downwardly extending shank 43 terminating in a boss 44 having a central bore screw-threaded to receive a pusher rod 45 held in position by a nut 46. Pusher rod 45 is provided with a bifurcated portion 47 adapted to accommodate

a roller 48 and is so adjusted that the roller rides with the traverse mechanism in advance of the cutter blade. The function of pusher rod 45 is to operate a lifter fork, the tines of which are adapted for insertion under, and lifting of the yarn body at the far end of the bobbin in order to place it in the path of the cutter blade 37 and insure the severance of the yarn body at that end. To accomplish this purpose roller 48 at the end of pusher rod 45 engages a lifter link 49 fulcrumed upon a pin 50 between the arms of bracket 4. Lifter link 49 is narrowed at its base for insertion and pivotal mounting in a slot 51 in lifter 52 which is provided with two forwardly projecting forks 53. Lifter 52 is biased to retracted position by springs 54, connected to a member 55 affixed to bracket 4. Bolted to member 55 is a stop member 56 carrying a roller 57 adapted to rest upon lifter 52. As roller 48 presses upon lifter link 49 the forks 53 are pushed forward and downward under the body of yarn on the bobbin, contacting the lowermost coils of yarn thereon and raising them in the path of the cutter blade to insure their severance thereby.

Connecting rod 19, pivoted at one end on bolt 17 is rotatably mounted at its other end upon a bolt 58 set in a crank wheel 59 near the periphery thereof and held in position by means of nut 60 and lock nut 61. Rotation of crank wheel 59, therefore, initiates the traverse movement of the cutter mechanism previously described. Crank wheel 59 is fixed upon one end of main drive shaft 62 supported in bearings 63 and 64 on standards 65 and 66 and driven by means of a pulley wheel 67 and belt 68 connected to a pulley 69, which in turn is driven by a motor 70 through the intermediary of pulley wheels 71 and 72 and belt 73, see Figure 1.

Further mounted upon main drive shaft 62 is a sprocket wheel 74 connected by chain 75 to a second sprocket wheel 76 fixed on doffer shaft 77, which controls the mechanism by which the waste-bearing bobbins are fed to the cutting mechanism and doffed after stripping is complete. Doffer shaft 77 has its ends mounted in bearings in standard 78 and bracket 5. Bracket 5 is bifurcated to receive a cam 79 fixed upon shaft 77 and mounted between the arms of a crosshead 80 having slots 81 therein for sliding engagement with the shaft 77. Crosshead 80 is further provided at its end with a shaft 83 fixed between the arms thereof, upon which is mounted in bearings a cam following roller 84, actuated by cam 79 at each revolution of doffer shaft 77 and adapted to contact the lower surface of a link 85, one end of which is mounted for rotation on an axle 86 fixed between arms 87 and 88, projecting from bracket 5. The other end of link 85 is pivotally connected to the two arms of a connecting link 89, the other end of the latter being pivotally connected to lifter rod 10 by a bolt 90. Inasmuch as the ratio of rotation of main drive shaft 62 to that of doffer shaft 77 is two-to-one, crank wheel 59 makes two revolutions for each revolution of cam 79, so that after two strokes of cutting member 34, cam 79 operates to raise lifter rod 10, and with it the cutter 34 during its second return stroke. Lifter rod 10 is raised when cam 79 causes cam roller 84 to press against the lower surface of link 85. Coincident with this action, crosshead 80, in the end of which the cam roller 84 is mounted, is retracted, releasing the mechanism by which the bobbin is held during the cutting operation.

The end of crosshead 80 opposite the end car-

rying the cam roller 84 is screw-threaded to receive a plunger rod 91 fastened securely to the crosshead by nuts 92 and 93. The other end of plunger rod 91 is screwed into a plunger 94 of larger diameter than the plunger rod, said plunger being supported in bearing 95, carried by bracket 96 affixed to the table top. A tight connection is maintained between plunger rod 91 and plunger 94 by means of a nut 97. Plunger 94 is adapted to reciprocate in bearing 95 and terminates in an enlarged frusto-conical member 98 adapted to engage the open end of a waste-bearing bobbin 99, see Figure 4. Plunger rod 91 is surrounded by a spring 100, one end of which rests against the abutment formed by plunger 94, the spring being enclosed in a housing comprising a sleeve 101 and a pack nut 102, which forms an abutment for the other end of spring 100. Spring 100 serves to bias plunger 94 toward insertion in the open end of the bobbin, retraction of crosshead 80 causing the plunger to be withdrawn.

Affixed to the base of crosshead 80, at a point on a vertical line below its connection with plunger rod 91, is a connecting rod 103 secured by means of nuts 104 and 105. Connecting rod 103 lies in a plane parallel to cutter bar 18, and its other end terminates in a coupling 106 bearing a pin 107, upon which one end of a link 108 is pivotally mounted. The opposite end of link 108 is inserted in a slot 109 provided in plunger 110, and is mounted for pivotal movement therein by means of a bolt 111. Link 108 is further pivoted at a point intermediate its ends upon a pin 112 mounted between arm 113 and 114 secured to the walls of bracket 4. Plunger 110 is supported in a guide 115 in bracket 4 and terminates in a frusto-conical member 116 positioned opposite to frusto-conical member 98 and adapted to engage the opposite open end of waste-bearing bobbin 99. Plunger 110 is biased to the bobbin-engaging position by springs 117 and 118 attached to opposite ends of a crosspiece 119, passed through the end of the plunger. The ends of springs 117 and 118 remote from the connection to crosspiece 119 are affixed to member 4 as shown in Figure 2. It will be seen that when cam 79, during rotation, presses against cam roller 84, plungers 94 and 110 are simultaneously retracted out of engagement with bobbin 99.

Doffer shaft 77, in addition to carrying the cam 79, which operates the cutter lifting and bobbin clamping mechanism, also controls the movement of the endless conveyor by which bobbins are conveyed to and discharged from the stripper mechanism and subsequently conveyed to the spraying device. For this purpose, doffer shaft 77 carries a miter gear 120 meshing with a bevel gear 121 affixed to a shaft 122, mounted in bearings in pillow block 123. Shaft 122 carries a sprocket wheel 124 which, through the intermediary of chain 125 and a second sprocket wheel 126, affixed to a shaft 127, drives the conveyor mechanism. The periodic advance of the conveyor is effected by providing miter gear 120 with teeth 128 on only a small arc of its periphery, so that meshing with gear wheel 121 occurs for only a short period for each revolution of the gear 120.

Shaft 127, from which the endless conveyor is driven, has its ends mounted in bearings in pillow blocks 129 and 130, and carries in addition to sprocket wheel 126, a pair of spaced sprockets 131 and 132, designed to mesh respectively with endless conveyor chains 133 and 134, the opposite

ends of which mesh with sprockets 135 and 136 affixed to shaft 137, the ends of which are mounted in bearings in pillow blocks 138 and 139.

Intermediate the pairs of sprockets, the conveyor chains are supported by runners 140 and 141. Every third link of conveyor chains 133 and 134 is provided with a forked bobbin holder cradle 144 adapted to fit the outer surface of a bobbin, the holders on opposite conveyor chains cradling opposite ends of the bobbin. The base of each holder 144 is provided with a flange 145 fastened by means of a bolt to a flange 147 of the inner half of the conveyor chain link.

Thus, opposite ends of a bobbin are supported by oppositely disposed holders 144. When a bobbin carried along by the conveyor reaches a position in axial alignment with plungers 84 and 110, its ends are engaged and tightly held by frustoconical members 88 and 116, due to the biasing action of springs 100, 117 and 118.

It will now be seen that, due to the ratio of rotation between main drive shaft 62 and doffer shaft 71, crank wheel 59 revolves twice for each revolution of miter gear 120 and cam 78. Therefore, when a bobbin has been placed in position for yarn severing, the reciprocating mechanism carrying the cutter blade twice traverses the length of the bobbin before same is doffed. After traveling across the bobbin the second time, and upon initiating its return trip, the teeth on miter gear 120 begin to mesh with the teeth 128 of gear wheel 121, and at the same time cam 78 engages cam roller 84. As cam 78 rotates it engages cam roller 84 and urges it against link 85, thus raising lifter rod 10 through the medium of connecting link 89, and lifting cutter blade 34 out of contact with the bobbin.

As cam roller 84 is displaced, crosshead 80 is retracted and plungers 84 and 110 disengaged from the open ends of the bobbin. At the same time, miter gear 120 meshes with gear wheel 121, the conveyor mechanism is actuated, and a new waste-filled bobbin carried into position between plungers 84 and 110. The teeth 128 on miter gear 120 then move out of engagement with gear wheel 121, and cam 78 passes from contact with roller 84, causing spring-biased plungers 84 and 110 to engage the newly positioned and immobilized bobbin.

At the beginning of a cutting operation cutter 34 rests upon the rim of the bobbin, and as the cutter moves forward over the surface of the bobbin pointed foot 38 rides under the coils of yarn and lifts them for severance by the sharp edge 39 of the blade. As the cutter approaches the other end of the bobbin, as set out in more detail hereinbefore, the roller 48 on the end of pusher rod 45 engages lifter link 49. As roller 48 presses upon lifter link 49 the forks 53 are pushed forward and downward upon the bobbin, contacting the lowermost coils of yarn and raising them to insure their severance by the cutting blade.

The bobbins, bearing waste which has been previously moistened by any suitable means in order to decrease its resistance to the cutting operation, are periodically fed to the stripping machine from a chute 148. This chute comprises an inclined base 149 supported by standards 150 and 151. The base of the chute is provided with flanges 152 and 153, offset inwardly to form guide tracks in which the rim of the bobbin rides on its way to the conveyor mechanism. Oppositely disposed guide tracks 154 and 155 are further provided, which serve the purpose of additionally confining and preventing displacement of the

bobbin. The lower ends of guide tracks 154 and 155 are affixed to standards 150 and 151 and are curved downward to direct the bobbins into the holders 144 of the conveyor mechanism. The other ends are affixed to uprights 156 and 157. Intermediate the ends guide tracks 155 are connected by crosspiece 158.

The bobbins are retained in the chute until the conveyor mechanism is ready to receive them, 10 by means of a crossbar 159, which is, in effect, an extension of the base 149. Crossbar 159 is affixed to a rod 160 by means of flanges 161 and 162, forming disconnected extensions of flanges 152 and 153. The ends of rod 160 are pivotally 15 mounted in bearings in standards 150 and 151. The end of rod 160 projecting beyond standard 150 is inserted in a boss 163 at the end of a lever 164 and is affixed thereto by a set screw 165. Crossbar 159 is biased to the closed position, that 20 is, the position in which it acts as a stop for the bobbins, by a spring 166, one end of which is attached to lever 164 and the other end to bracket 4. The opposite end of lever 164 is pivotally connected to a link 167 by means of a bolt 168 mounted for sliding engagement in a slot 169. Link 167 is fulcrumed about a bolt 170 affixed to standard 150, and its free end extending downward in the path of pins 171, which project at spaced points near the periphery of a wheel 172 25 mounted upon drive shaft 121 for the bobbin conveyor. During each periodic rotation of shaft 121, wheel 172 turns, and one of the pins 171 contacts the free end of link 167, causing it to rotate about its point of pivot and, through 30 the medium of lever 164, causing crossbar 159 to be depressed, thus allowing a bobbin to drop 35 from the chute to the conveyor at the completion of the movement of the latter.

The bobbin conveyor is actuated periodically 40 to convey successive waste-filled bobbins to a position in axial alignment with plungers 84 and 110. These intervals, as stated before, are controlled by the number of teeth with which miter gear 120 is provided. In the preferred embodiment of the invention the teeth cover only a small arc of the gear's surface, so that with each revolution of miter gear 120 its teeth 128 mesh with gear wheel 121 for an interval sufficient to discharge a stripped bobbin from between 45 plungers 84 and 110 and replace it with a succeeding waste-filled bobbin. As already explained, the period during which the bobbin is immobilized, that is, the period during which the conveyor is not actuated, is sufficient to allow the cutter blade to pass twice from one end of the bobbin to the other. Each movement of the conveyor causes sufficient movement of wheel 172 to cause member 159 to release one 50 bobbin.

After the body of waste yarn has been cut and the bobbins discharged from the cutter, they are advanced to the end of the machine. Suspended above the conveyor are one or more pipes 173, closed at one end and connected by 55 pipes 174 to a common conduit 175, leading to a source of water supply. Pipes 173 are provided on their under surface with orifices 176 from which water is discharged upon the bobbins as they pass thereunder. Pipes 173 are so spaced 60 that each lies vertically above and in axial alignment with a bobbin when it is rendered intermittently stationary due to the intermittent movement of the conveyor. The spray is discharged 65 radially of the bobbin into the kerf in the yarn 70 75

body made by the cutter blade. The moist waste yarn clinging to the bobbin is thus removed. The waste yarn drops into a wire basket 177 and the water carried off in a trough 178 situated therebelow. The empty bobbins continue to travel with the conveyor until they reach a curved platform 179 supported by standard 180 affixed to crosspiece 181. As the bobbins move up platform 179 they are lifted out of holders 144 and are removed by hand or drop from the end of the platform into a basket or other suitable container.

It is to be noted that two trips of the cutting blade are provided merely as a safety measure to insure the cutting of all coils of yarn. With this method of operation, bobbins pass through the machine at the rate of forty-three per minute. However, it is obvious that if the second stroke of the cutter mechanism is eliminated this speed may be doubled. Inasmuch as the speed ratio of drive shaft 62 to doffer shaft 77 is two-to-one the single stroke of the cutter may be effected by simply substituting in place of sprocket 76 on shaft 77, a sprocket wheel of the same size as sprocket 74 on the main drive shaft. The two shafts will then be driven at the same rate of speed.

Having now described the invention in detail, it is to be understood that variations may be made in the number and arrangement of parts without departing from the spirit of the invention or the scope of the appended claims.

What is claimed is:

1. In an apparatus for automatically removing waste yarn from bobbins, means for gripping and holding the opposite ends of a bobbin, means for periodically feeding bobbins to said gripping and holding means, power means for alternately actuating said feeding means and said gripping and holding means, reciprocating cutting means arranged to move axially of a gripped bobbin between the surface thereof and the yarn thereon to sever the coils of the latter, and means for driving said cutting means during the gripping period of said gripping and holding means.

2. In an apparatus for automatically removing waste yarn from bobbins, means for holding a bobbin in fixed position, means for periodically successively feeding a plurality of bobbins to said holding means, power means for alternately actuating said feeding means and said holding means, reciprocating cutting means arranged to move axially of a bobbin supported by said holding means, said cutting means including a bobbin-contacting foot portion of a contour conforming to that of the surface of a bobbin and an upstanding cutting edge arranged to sever the coils of the yarn raised from the surface of the bobbin by said foot, and means for driving said cutting means during the holding period of said holding means.

3. In an apparatus for automatically removing waste yarn from bobbins, a conveyor for supporting simultaneously a plurality of bobbins in equally spaced relationship, said conveyor being periodically moved to an extent equal to the distance between bobbins, means for successively gripping opposite ends of each bobbin during a period of immobilization thereof, reciprocating cutting means arranged to move axially of the gripped bobbin between the surface thereof and the yarn thereon to sever the coils of the latter, and means for intermittently driving said conveyor and, during the period

in which the conveyor is immobilized, said means concurrently actuating said gripping means and said cutting means.

4. In an apparatus for automatically removing waste yarn from bobbins, a conveyor for supporting simultaneously a plurality of bobbins in equally spaced relationship, said conveyor being periodically moved to an extent equal to the distance between bobbins, means for successively gripping opposite ends of each bobbin during a period of immobilization thereof, a reciprocating mechanism arranged to move axially of a gripped bobbin, cutting means affixed to said reciprocating mechanism, said cutting means having a foot arranged for insertion under the coils of yarn at one end of said bobbin, means driven by said reciprocating mechanism for raising the coils of yarn at the opposite end of said bobbin in the path of said cutting means, and means for intermittently driving said conveyor and, during the period in which the conveyor is immobilized, said means concurrently actuating said gripping means and said cutting means.

5. Apparatus for successively stripping yarn from a plurality of bobbins comprising, an endless conveyor provided with a plurality of spaced bobbin holding elements, means for periodically and intermittently moving unidirectionally said conveyor a distance equal to that between holding elements to cause each of said elements successively to occupy equidistant stations, a bobbin storage chute adjacent one station, said chute having a discharge mouth arranged to register with a bobbin carrying element, means actuated by said conveyor moving means for discharging the bobbin from said chute onto one of said elements upon completion of each movement of said conveyor, means disposed adjacent a subsequent station for severing the yarn body on a bobbin, a plurality of means disposed adjacent stations subsequent to that at which severing occurs for removing the yarn body from the bobbin while said bobbin is carried by said conveyor, and means for actuating said severing means intermediate each movement of said conveyor.

6. Apparatus for successively stripping yarn from a plurality of bobbins comprising, an endless conveyor provided with a plurality of equally spaced bobbin holding elements, means for periodically and intermittently moving said conveyor a distance equal to that between holding elements to cause each of said elements successively to occupy equidistant stations, a bobbin storage chute adjacent one station, said chute having a discharge mouth arranged to register with a bobbin carrying element, means actuated by said conveyor moving means for discharging a bobbin from said chute onto one of said elements upon completion of each movement of said conveyor, means disposed adjacent a subsequent station for severing the yarn body on a bobbin while said bobbin is carried by said conveyor, and means for actuating said severing means intermediate each movement of said conveyor.

7. Apparatus for successively stripping yarn from a plurality of bobbins comprising, an endless conveyor provided with a plurality of equally spaced bobbin holding elements, means for periodically moving said conveyor a distance equal to that between holding elements to cause each of said elements successively to occupy equidistant stations, a bobbin storage chute adjacent one station, said chute having a discharge mouth arranged to register with a bobbin carrying ele-

ment, means associated with said conveyor moving means for discharging a bobbin from said chute onto one of said elements upon completion of each movement of said conveyor, means disposed adjacent a subsequent station for severing along a straight line the yarn body on a bobbin, means disposed adjacent a station subsequent to that at which severing occurs for spraying a fluid on said yarn body along the line of severance thereof to remove said body from said bobbin, and means for actuating said severing means intermediate each movement of said conveyor.

8. Apparatus for successively stripping yarn from a plurality of bobbins comprising, an endless conveyor provided with a plurality of equally spaced bobbin holding elements, means for periodically moving said conveyor a distance equal to that between holding elements to cause each of said elements successively to occupy equidistant stations, a bobbin storage chute adjacent one station, said chute having a discharge mouth arranged to register with a bobbin carrying element, means associated with said conveyor moving means for discharging a bobbin from said chute onto one of said elements upon completion of each movement of said conveyor, means disposed adjacent a subsequent station for severing along a straight line the yarn body on a bobbin, means disposed adjacent a station subsequent to that at which severing occurs for spraying a fluid on said yarn body along the line of severance thereof to remove said body from said bobbin, means for actuating said severing means intermediate each movement of said conveyor, and means for successively removing stripped bobbins from said conveyor at a station subsequent to that at which spraying occurs.

9. Apparatus for successively stripping yarn from a plurality of bobbins comprising, an endless conveyor provided with a plurality of equally spaced bobbin holding cradles, means for periodically moving said conveyor a distance equal to that between cradles to cause each of said cradles successively to occupy equidistant stations, a bobbin storage chute adjacent one sta-

tion, said chute having a discharge mouth arranged to register with a bobbin carrying cradle, means associated with said conveyor moving means for discharging a bobbin from said chute onto one of said cradles upon completion of each movement of said conveyor, means disposed adjacent the next station for severing along a straight line the yarn body on a bobbin, means for holding the bobbin during severing, means disposed adjacent stations subsequent to that at which severing occurs for spraying a washing liquid on said yarn body along the line of severance thereof to remove said body from said bobbin and to wash the latter, means for actuating said severing and holding means intermediate each movement of said conveyor, and means for successively removing bobbins from said cradles at a station subsequent to that at which washing occurs.

10. A bobbin stripping machine comprising in combination, an endless conveyor, means for feeding waste-filled bobbins to said conveyor, a reciprocating mechanism positioned above said conveyor adapted to move in a horizontal plane axially of said bobbins, a knife blade affixed to said reciprocating mechanism, said knife blade having an upright cutting edge and an arcuate foot shaped to fit the surface of a bobbin and to ride along the surface thereof without injury thereto, means actuated by said reciprocating mechanism arranged to engage the coils of yarn at one end of said bobbin and raise them in the path of said cutting edge, a main drive shaft from which said reciprocating mechanism is driven, a secondary drive shaft driven from said main drive shaft, means associated with said secondary drive shaft for driving said endless conveyor at spaced intervals, means actuated in timed relationship with the movement of said endless conveyor for holding successive bobbins stationary during two strokes of said reciprocating mechanism, and means associated with said endless conveyor for removing the severed yarn from said bobbins.
